CLAIM

The ornamental design for a holder for a safety razor, as shown and described.

DESCRIPTION

FIG. 1 is a front elevational view of the holder for a safety razor showing our new design;

FIG. 2 is a rear elevational view thereof;

FIG. 3 is a top plan view thereof, the bottom view being a mirror image of the plan view;

FIG. 4 is left side elevational view thereof;

FIG. 5 is a right side elevational view thereof; and,

FIG. 6 is an enlarged cross sectional view taken along the line 6—6 in FIG. 1.

The portions shown in broken lines are for illustrative purposes only; neither these broken lines nor the unshaded areas within the surrounding ellipses form any part of the claimed design.
